United States Patent Office

Des. 189,303
Patented Nov. 22, 1960

189,303

CLOCK

Gordon Florian, Bridgeport, Conn., assignor to Sunbeam Corporation, Chicago, Ill., a corporation of Illinois

Filed Aug. 7, 1958, Ser. No. 52,108

Term of patent 14 years

(Cl. D42—7)

Fig. 1 is a front elevational view of the clock showing my new design;

Fig. 2 is a right side elevational view thereof; and

Fig. 3 is a top plan view thereof.

The dominant features of the design reside in the portions shown in full lines.

I claim:

The ornamental design for a clock, as shown and described.
